BUTCHER'S GAMBREL

Original Filed May 8, 1928

J. O. Benton

By Watson E. Coleman
Attorney

UNITED STATES PATENT OFFICE

JAMES OSCAR BENTON, OF GUTHRIE, IOWA

BUTCHER'S GAMBREL

Refile of application Serial No. 276,090, filed May 8, 1928. This application filed July 10, 1930. Serial No. 467,107.

This invention relates to gambrels used by butchers in suspending animals in butchering and particularly to the gambrel shown in the application filed by me on May 8, 1928, Serial No. 276,090 which application has lapsed for nonpayment of final fee.

The general object of this invention is to provide a very simple gambrel of this character having the hooked carcass-engaging levers mounted upon an intermediate supporting bar and having a single chain connected to said levers whereby when the chain is slack the hooked levers may be drawn inward to their full extent and when strain comes upon the chain the hooked levers will be forced outward so that the carcass will be spread.

My invention is illustrated in the accompanying drawings, wherein:—

Figure 1 is a top plan view of a gambrel constructed in accordance with my invention;

Figure 2 is a top plan view of the body of the gambrel.

Referring to the drawings, 10 designates a cross bar which may be made of two sections bolted or riveted to each other in spaced relation. Mounted in said cross bar adjacent the middle thereof are the pulleys 11.

Pivoted to the ends of the cross bar are the levers 12 having hooks 13 at their lower ends, the upper ends of the levers being connected to chains 14 which extend below the pulleys 11 and then extend upward to a ring or like device 16.

It will be understood that while I have referred to two chains 14 that a single chain is used and that this single chain is connected to the ring or loop 16 so that the gambrel may be supported. The two chains or the two ends of the chain extend inward from the upper ends of the levers and over pulleys 17 which guide the chain beneath the pulleys 11.

It will be seen from Figure 1 that the levers, which are preferably about 18" in length, may be drawn inward so as to be engaged with a carcass and then when strain is placed upon the ring 16 the weight of the carcass will cause the lower ends of the levers to be forced outward and the carcass to be spread.

This gambrel is very simple, it may be

readily applied, and the hooked levers may be drawn inward so that they will not be more than 17" apart but when expanded they will be some 54" apart.

I claim:—

1. A butcher's gambrel of the character described comprising a cross bar having a pair of pulleys disposed one on each side of the middle thereof, and a pair of guide pulleys exterior to the first named pulleys, levers pivoted to the ends of the cross bar and having hooks at their lower ends, a single chain having its ends connected to said levers remote from the hooks, passed over the second named pulleys and beneath the first named pulleys, and extending upward in a bight above the middle of the cross bar. 55

2. A butcher's gambrel of the character described comprising a cross bar formed in two sections spaced from each other, a pair of pulleys disposed between said sections adjacent to but one on each side of the middle of the bar, a pair of guide pulleys disposed outwardly of the first named pulleys, levers pivoted between the sections of the cross bar 70 and at their lower ends formed with hooks, and a single chain connected at its ends to said levers, the chain passing inwardly from each lever over one of the guide pulleys and beneath one of the first named pulleys and then upward to form a bight portion disposed above the middle of the cross bar, and a ring through which the bight of the chain loosely passes. 75

In testimony whereof I hereunto affix my signature.

JAMES OSCAR BENTON.
